(57) **CLAIM**

The ornamental design for a stereotactic head frame localizer, as shown and described.

DESCRIPTION

FIG. 1 is a top, right, front perspective view of the stereotactic head frame localizer according to the present design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a left, top, rear perspective view thereof.

The broken lines shown in the drawings are for illustrative purposes only and form no part of the claimed design.
